UNITED STATES PATENT OFFICE.

FREDERICK WILLIAM VICKERY, OF LONDON, ENGLAND.

FUSE FOR PROJECTILES.

1,309,709.

Specification of Letters Patent. Patented July 15, 1919.

Application filed April 28, 1919. Serial No. 293,288.

To all whom it may concern:

Be it known that I, FREDERICK WILLIAM VICKERY, a subject of the King of Great Britain and Ireland, and residing at 5 Devonshire Grove, Old Kent Road, London, S. E., England, have invented certain new and useful Improvements in Fuses for Projectiles, of which the following is a specification.

10 This invention relates to percussion fuses for projectiles of the kind in which an inertia-collar encircling a stem forming part of the inertia pellet to which the striker needle or detonator is secured operates to prevent the outward motion of a locking means engaged between the striker and detonator elements for a period of time after the projectile with which the fuse is associated has been launched in flight and to permit such outward movement on the acceleration of the projectile falling below a certain predetermined value.

15 A fuse according to the invention comprises an inertia collar encircling a stem forming part of the inertia pellet to which the striker needle or detonator is secured and retaining a resilient member between the striker and detonator elements in such manner that the motion of the inertia collar consequent upon the positive acceleration of the projectile, acts to release the resilient member, and the movement of the inertia pellet to which the striker needle or detonator is secured as a result of the acceleration 20 of the projectile falling below a certain value, completely frees the resilient member and thus permits relative motion between the striker and detonator elements to fire the detonator on the velocity of the projectile being suddenly reduced.

25 The resilient member is conveniently in the form of a spiral spring resembling a clock spring.

30 The inertia collar may in accordance with the invention be so formed that a shock of a predetermined magnitude causes the conformation of the inertia collar to be altered and thus enables the member to operate to release the resilient member.

35 The inertia collar may be a spring clip adapted to grip the stem of the detonator pellet or it may be a ring provided with portions adapted to hold the collar in fixed relationship with the stem it encircles; thus 40 the collar may be provided with fingers which are bent so as to bear upon the upper

edge of the stem and are so dimensioned that a shock of a predetermined magnitude will cause the fingers to be moved sufficiently to allow the collar to slide to the rear of the 45 stem.

These fingers may be formed by making cuts in the collar so as to leave between adjacent cuts a portion of metal of such size that when the portions are bent inward they 50 will hold the collar in a position to retain the resilient member, but will, under the action of a shock of predetermined magnitude, be moved outward to enable the collar to travel to the rear of the stem.

For instance, a collar may be provided with two pairs of cuts so as to leave between each member of a pair a relatively narrow strip or finger of metal of a length which may be equal to three-fourths the depth of 55 the ring. These strips or fingers are given an inward set so as to cause them to engage above the stem about which the collar is mounted. Thus, for instance, they may be bent inward gradually for about one-half 60 their length, and for the remaining portion they may be parallel with the axis of the ring.

The invention will be further described in its relation to a fuse of the kind in which 65 firing results in the event of the projectile striking an object at certain angles, by the wedging action of a body confined between suitably formed surfaces, as, for instance, two coned surfaces.

70 While, as will be understood, the firing mechanism in accordance with the invention, may be employed with grenades and other projectiles, a form of firing mechanism adapted for use with a shell will be described.

75 The body may be of any suitable form, but is preferably cylindrical, bored axially for a certain distance from one end with a hole of a certain diameter and from the other end with a hole of a less diameter so that a shoulder is formed at the junction of the two 80 holes.

85 The smaller of the holes is tapped for securing the ignition mechanism or fuse to the shell, the larger being adapted to act as the chamber in which the mechanism of the fuse is housed and being tapped to enable a cap 90 to be screwed in to close this chamber.

95 In this chamber a body on one side of 100 which the flash powder is held, and on the other side of which is formed a conical

seating, is arranged to rest on the aforesaid shoulder with the side holding the flash powder directed toward the end of the fuse adapted to be secured to the shell.

5 On the conical seating, a detonator holder suitably formed with, for instance, a spherical surfaced end, in which the detonator is secured, is arranged in contact with the seating and normally resting in the center of 10 the conical seating. The center of this detonator holder is drilled to admit a striker needle and to house a spring which operates normally to keep the striker needle from coming into contact with the detonator. A 15 head provided with a suitably formed, preferably, a spherical surface, is provided on the needle and this head is seated in the conical seating formed in the cap, or closing device of the chamber housing the detonator mechanism.

The distance between the conical seatings, and the combined length of the detonator holder and the striker needle with its head and with the intervening spring, are such 25 that the spring referred to is held in compression and itself acts to keep the base of the detonator holder and the head of the striker needle centrally disposed in respect to the axis of the conical seatings.

30 The strength of the compression spring is adjusted to the degree which suffices normally to prevent relative motion between the striker needle and detonator, and yet to permit such relative motion on the sudden interruption of the flight of the projectile, caused by its impact on an object, resulting either in the members being displaced from their central position and their end surfaces being caused to travel up the inclined surfaces of the conical seatings, thus bringing 35 the detonator and needle together, or in relative longitudinal movement of the detonator or holder in the absence of such displacement of the detonator device from its central position, according to the angle at which the projectile strikes the object.

Two embodiments of the invention are illustrated by way of example in the accompanying drawings, in which:—

50 Figure 1 is a view partly in section; Fig. 2 is a plan thereof; while Figs. 3 and 4 are elevations of a detail; Fig. 5 is a corresponding plan of one construction; Fig. 6 is a sectional elevation; Fig. 7 is an outside elevation; and Fig. 8 is a plan of a second construction, while

60 Figs. 9 and 10 are respectively a section and plan of the inertia collar employed in this construction.

In the drawings, 1 is the fuse body, provided with an internal screw-thread 2, for effecting connection with the shell and with 65 an internal screw-thread 3, which engages

a corresponding thread on the cap 4 serving to close the chamber 5. At the base of this chamber, the primer 6 is arranged and in contact with a conical surface of the upper side of this primer, the detonator pellet 7 70 provided with a socket 8 of the detonator is supported. With the detonator pellet the striker pellet comprising a spherical or conical surfaced head 9, a cylindrical body 10, and a striker needle 11, co-operates, a 75 spiral spring 12 being arranged to maintain, normally, the desired relationship as regards position between the detonator pellet and the striker pellet.

Around the cylindrical body 10 of the 80 striker pellet a strip or band of spring steel 13 is wound, and this strip or band is confined by the inertia collar 14.

A safety-pin 15 is passed through holes in the body and, as shown, prevents, so long as 85 the pin is in position, motion of the inertia collar in a longitudinal direction.

Within the chamber and in frictional contact with the walls thereof, a spring ring 16, the construction of which is shown more 90 clearly in Figs. 3, 4 and 5, is arranged. This ring is split at 17 and is provided with holes 18 and 18^a through which also the safety-pin 15 passes.

In the construction shown in Figs. 6 to 10 95 the inertia collar 14 is provided with two pairs of cuts leaving two narrow strips or fingers of metal 14^a which are bent inward and support the collar in place on the detonator pellet and in the under surface of 100 the head 9 of the striker pellet, a groove or depression 9^a is formed.

The operation of the fuse illustrated by Figs. 1 to 5 is as follows:—

The safety-pin 15 is withdrawn prior to 105 the discharge of the projectile with which the fuse is associated.

In consequence of the acceleration of the projectile on its discharge, the striker pellet will be caused to move rearwardly in the 110 chamber 5 as also will be the inertia collar 14 and the spring ring 16. The movement of the spring ring 16 will cause the ring to cover the holes provided in the fuse body for the safety-pin and will thus prevent 115 dirt entering this chamber by way of these holes.

As a result of the rearward movement of the inertia collar 14, the spring 13 will no longer be confined by it, but the rearward 120 motion of the striker pellet will cause the spring band to be held between the underside of the head 9 of the striker pellet and the upper end of the detonator pellet 7, and thus further motion of the striker needle in 125 relation to the detonator will be prevented. When the acceleration of the projectile with which the fuse is associated falls below a predetermined positive value, the spring 12 will cause the striker pellet and detonator 130

5 pellet to move apart; the spring 13 will then no longer be held between the underside of the head 9 of the striker pellet and the upper end of the detonator pellet and will therefore uncoil and, in expanding, will take up a position in which it will no longer prevent relative position between the striker pellet and the detonator pellet to explode 10 the detonator, which motion will take place as a result of the projectile striking an object, and will result in the ignition of the bursting charge in the projectile.

15 The operation of the construction illustrated in Figs. 6 to 10 is quite similar except that the acceleration of the projectile on its discharge from the gun causes the fingers 14^a to be bent or wedged outward thus permitting the collar 14 to move to the rear of the chamber 5, the spring band 13 being then no longer confined by it. The 20 striker pellet being however, simultaneously caused to move toward the rear end of the chamber will, however, cause the spring band 13 to be engaged in the groove or depression 9^a formed in its head, such action 25 serving to retain the spring band between the striker and detonator pellets until the acceleration of the projectile has fallen below a certain positive value when the spring 30 band 12 will cause the striker and detonator pellets to move apart and set free the spring band 12, thus permitting it to take up a position in which it will no longer prevent relative motion between the striker and detonator pellets, to explode the detonator.

35 Having now described my invention, what I claim as new and desire to secure by Letters Patent is:—

1. A fuse for projectiles including in

combination, an attaching body having a 40 chamber, a closure cap for the chamber, a primer seated in the chamber, a striker pellet having a cylindrical body, a detonator pellet having a tubular stem designed to receive the body of the striker pellet, spring 45 means between the pellets for yieldingly holding them respectively against the cap and the primer, a clock spring arranged about the body of the striker pellet and positioned between the head of the striker 50 pellet and the end of the stem of the detonator pellet, and an inertia collar frictionally engaged with the outer surface of the stem of the detonator pellet and with the outer surface of the clock spring. 55

2. A fuse for projectiles including in combination, an attaching body formed with a chamber having opposed openings in the walls, a cap for closing the chamber, a split ring frictionally engaged with the inner surface of the chamber, a primer seated in the chamber, coactive striker and detonator pellets in the chamber, spring means between the pellets for yieldingly holding them respectively against the cap and 60 primer, a resilient member arranged about the body of the striker pellet and between the head of said striker pellet and the end of the detonator pellet, an inertia band frictionally engaged with the detonator pellet and the resilient member, and a locking pin removably engaged through the openings in the chamber and with the split ring and beneath the inertia collar. 65

70 In testimony whereof I have signed my name to this specification.

FREDERICK WILLIAM VICKERY.
